UNITED STATES PATENT OFFICE.

ALEXANDER DUNCAN JANSEN, OF JOHANNESBURG, SOUTH AFRICAN REPUBLIC.

APPARATUS FOR CHARGING OR DISCHARGING CYANID-VATS, &c.

SPECIFICATION forming part of Letters Patent No. 687,920, dated December 3, 1901.

Application filed July 5, 1899. Serial No. 722,873. (No model.)

To all whom it may concern:

Be it known that I, ALEXANDER DUNCAN JANSEN, a subject of the Queen of Great Britain and Ireland, and a resident in Royal Chambers, Simmonds street, Johannesburg, in the South African Republic, have invented certain new and useful improvements in and relating to apparatus for charging or discharging, particularly adapted for use in connection with the discharging, &c., of cyanid-vats and the like, of which the following is a specification.

This invention relates to improvements in connection with charging waste products, and is particularly designed with the object of doing away with manual labor in the process thereof.

The invention is particularly adapted for use in connection with the discharging of cyanid-tanks employed in the process of extraction of precious metals from reduced ores.

The reduced ore or "sands" after having been treated with cyanid solution have to be discharged either from one tank to a second or from the second tank to the dumping-site, whereby a great amount of manual labor is involved, owing to the fact that it is necessary to handle the tailings or sands twice.

By this invention the uppermost tank (or that one in which the first treatment is carried out) is automatically emptied into a second tank which is placed beneath it. From this second tank the tailings or sands are discharged onto a conveyer, as hereinafter described, which deposits the tailings to be discharged into a sump. From this sump the tailings are withdrawn and transported to the dumping-site by means of an improved conveyer, for which application for a patent has been lodged at the same time with this present application.

My invention will be fully described on referring to the accompanying drawings, in which—

Figure 1 shows a general view of the arrangement of my apparatus in relation to two cyanid-tanks, one being placed above the other in the ordinary manner. Fig. 2 shows a plan view of rotating scraping-arms and doors at the bottom of the tank; Fig. 3, a detail sectional view of scraping-arm; Fig. 4, a

vertical section through the discharging apparatus adapted to the lower tank; Fig. 5, an enlarged plan view showing bearing-block B in relation to framework C and outer hollow shaft D in section; Fig. 6, a vertical section through the discharging apparatus adapted to the upper tank.

Referring to the drawings, in which the mechanism for emptying the lower tank is shown, A is a central vertical rotary shaft formed at its upper end with a collar or block A', rigidly secured thereto.

B is a bearing-block bored so that the central shaft A may easily pass through it and machined on its upper surface to form a race for the balls or rollers B', which are interposed between the collar A' and the bearing-block B and are free to revolve thereupon independently. The bearing-block B is provided with projections or wings B², which project through longitudinal slots cut in the vertical fixed framework C, so that the said block B slides vertically in the guides thus formed in the vertical framework C. The central rotatory shaft A while revolving may be raised or lowered by this means. This raising or lowering of the bearing-block B is automatically accomplished by means of an outer hollow rotatory shaft D of an inside diameter sufficient to contain within it all the previously-described mechanism, the said hollow shaft D being cut on its inside surface with a screw-thread which engages a corresponding male screw-thread cut upon the outer surfaces of the projections B², which project beyond or outside the fixed vertical framework C. The outer hollow shaft D is furnished at its lower end with a spur-wheel D', which is rigidly secured thereto and stiffened by means of the brackets, as shown.

The said spur-wheel D', with outer hollow shaft D attached, is supported by means of the roller or ball bearings D², the lower races of which are formed in the fixed framework C', to which the vertical upright framework C, already mentioned, is firmly secured. The said vertical fixed framework C is of tubular construction, provided with vertical slots through which the wings B², attached to the bearing-block B, project.

At the bottom of the central rotatory shaft

- A set of scraping-arms E are attached of a radius slightly less than the radius of the tank in which they are intended to revolve. Motion is imparted to the hollow shaft D by 5 means of a pinion F, which gears with the teeth on the spur-wheel D'. This action causes the central rotatory shaft A, with scraping-arms E attached, to rise or fall according to the direction in which the pinion 10 F is driven owing to the screw-threads on the projections B² gearing with the internal screw-thread of the hollow shaft D. The central shaft A, with arms E attached, is also simultaneously caused to revolve by the same 15 pinion F driving a lower spur-wheel G, which is supported from the fixed framework C' by means of the ball-bearings G'. The fixed framework C' is constructed with a projecting piece C³, which is recessed so as to form 20 the lower seating for the balls G'. Corresponding projecting pieces G² are bolted to the spur-wheel G, forming the upper bearing-surface for the balls G'. The shaft A is provided with longitudinal projections A², 25 and the central boss of the spur-wheel G is machined with corresponding longitudinal recesses. By this construction the rotatory motion of the spur-wheel G is communicated to the central shaft A without interfering with 30 its upward-and-downward motion, thus allowing it to rise or fall according to the impulse of the hollow shaft D with the screw-thread on its inner surface actuating the bearing-block B.
- 35 With reference to the upper tank, H is a center fixed tube rigidly secured at its base to the bottom of the upper tank, the internal diameter of the said tube H being such as to receive the hollow shaft D of the lower tank 40 and the whole of the mechanism inside D when it is at its highest, the object of this construction being to avoid the necessity of increasing the distance between the two tanks, which would be necessary if the same arrangement as described in Fig. 4 were adapted to the upper tank.
- To the top of the fixed tube H a circular casting H' is rigidly secured, to which casting H' a further tube H², of larger diameter 45 than the inner tube H, is firmly keyed. To the bottom of tube H² is firmly secured a circular casting H³, which is machined on its upper side to form races for the balls H⁴.
- J is a spur-wheel provided with races on its 50 lower side to rest upon the balls H⁴ H⁴, aforementioned. J' is an outer tube or hollow shaft secured at its lower end to the spur-wheel J, so that the two revolve together, the hollow shaft J' being cut with an internal 55 screw-thread, as shown. The fixed tube or framework H² is formed with longitudinal slots k, through which the wings or projections K', rigidly secured to the upper end of another tube K², project, the outer surfaces of the 60 said wings K' being cut with a male screw-thread to correspond with and be engaged by the internal screw-thread of the hollow shaft

J'. The tube K, which passes downward easily in the space between the fixed framework formed by the two fixed tubes H and H², 70 terminates at its base in the boss K³, which boss K³ is machined to receive the ball-bearings K⁴.

L' L' L' are revolving scraping-arms secured to the hub or boss L, which is machined, as 75 shown, to form corresponding races for the balls K⁴, so that the arms L' rotate about the boss K³.

L² L² L² are rods secured at their lower ends to the revolving arms L', passing upward 80 through vertical slots or bushes L³, formed in the spur-wheel J, so that while the rods L² L² L² are free to rise or fall through the said bushes L³ L³ L³ yet the motion of the spur-wheel J as it revolves is transmitted, by means of the 85 rods L², to the revolving arms L'. Motion is imparted to the spur-wheel J by means of the pinion J², which is driven from any convenient motive source. The rods L² are preferably connected at their upper ends to an an- 90 nular framework L⁴ in order to stiffen them.

A⁴ is a central tie-rod passing through the center line of the discharging apparatus of both tanks, being secured at the lower end to the bottom tank and at the upper end to 95 the circular casting H', the object being to provide a central guide for the shaft A in its vertical motion.

K² is a light iron cylinder attached to the outer edge of the circular casting H' and in- 100 closing the whole of the mechanism of the top tank in order to prevent the dust and rain from entering.

V is the flexible pipe which conducts the sands about to be treated into the upper tank. 105

The construction of the scraping-arms is shown in cross-section in Fig. 3, from which it will be seen that each arm is composed of an ordinary rail E', with front and back plates E³, bolted thereto, the front or scraping plate E² being formed with a cutting edge e, as shown. The cutting edge is of course operative only when the arms are working in a downward direction into the tank, the discharge-doors at the bottom being open—i. e., when 115 the discharging apparatus is at work. On the return journey—i. e., when the tank is being filled with tailings for the next treatment—the revolving arms answer another purpose—viz., that of leveling the sands in the tank. 120

The revolving arms of the lower tank may also, if desired, be utilized as distributors of the cyanid solution when they are working upward in the tank and leveling the sands which are about to be treated by means of 125 the following construction: On referring to Fig. 3 it will be noticed that the construction of the arms is such as to provide a channel. By boring holes E⁴ at intervals it is obvious that if cyanid solution be introduced into the 130 aforementioned channels it will flow along the arms and pass through the holes E⁴ E⁴. At the bottom of the rotatory shaft A an annular trough E⁵ is fixed, from which pipes E⁶ are

led into the channel aforementioned formed by the upper portion of the scraping-arms E. The cyanid solution is led along the fixed pipe E⁷ into the fixed annular trough E⁸, which is provided with apertures at its bottom close to the rotatory shaft A, the number of the said apertures being regulated according to the flow required. The solution falls from the trough E⁸ around the shaft A into the trough E⁵, whence it is distributed through the pipes E⁶ into the revolving arms. The revolving arms of the upper tank may also, if desired, while stationary be utilized as distributors of the cyanid solution after the top tank has been filled with the sands requiring treatment. The cyanid solution is led along the fixed pipe T and falls into the box T' and thence into the arms L' L' L' and through the apertures therein onto the sands.

20 The operation of the part of my invention just described is as follows: Motion having been imparted to the pinion J² is communicated to the hollow shaft J', owing to J' being attached to the spur-wheel J, thereby causing the projecting wing K' and with it the tube K, with the rotatory arms L' L' L', attached, to rise or fall, according to the direction in which the apparatus is driven. At the same time the spur-wheel J rotating carries the rods L² L² L² around with it, and these rods communicate this rotatory motion to the arms L' L' L'.

Having now described my invention, what I claim as new, and desire to secure by Letters 35 Patent, is—

1. In combination with a cyanid or like tank, a vertical rotatory shaft, scraper-arms carried thereby, an outer hollow rotatory shaft having an interior screw-thread, and a block or nut 40 carried by the inner shaft and threaded to engage the threads of the outer shaft, said shaft being free to rotate within said nut but being prevented from longitudinal movement through the same, substantially as described.
- 45 2. In combination with a series of two tanks placed one above the other, a vertical rotatory shaft centrally of the lower tank, scraping-

arms carried thereby, a threaded bearing-block at the upper end of said shaft, in which block said shaft is permitted to rotate while 50 being held against longitudinal movement therethrough, an outer hollow shaft having interior screw-threads engaging said bearing-block, and means for driving said inner and outer shafts substantially as described. 55

3. In combination, a pair of tanks placed one above the other, a vertical rotatory shaft A centrally of said tanks, scraping-arms carried thereby within the lower tank, a threaded bearing-block at the upper end of said shaft, 60 in which block said shaft is permitted to rotate while being held against longitudinal movement therethrough, an outer hollow shaft having interior screw-threads engaging the bearing-block, means for operating said 65 shafts, a vertical tubular framework encircling the upper portions of said outer shaft and a tubular shaft K encircling said framework and having threaded projections, a tubular shaft J' encircling said shaft K, the projections carried by said tube or shaft K having threads engaging corresponding threads in shaft J', means for rotating the shaft J', a boss K³ on said shaft K within the upper tank, a hub L rotatably mounted thereon carrying scraping-arms, and means for rotating 70 said hub, substantially as described. 75

4. In combination, the pair of tanks situated one above the other, stirring mechanism for said upper tank, having a hollow supporting or operating mechanism, and stirring mechanism in said lower tank having its operating mechanism in line with the hollow mechanism of the upper tank and means for raising said operating mechanism of the lower 80 tank into said hollow mechanism of the upper tank, substantially as described. 85

In witness whereof I have hereunto set my hand in presence of two witnesses.

ALEXANDER DUNCAN JANSEN.
